UNITED STATES PATENT OFFICE

MICHAEL A. SCIULLO, OF VINELAND, NEW JERSEY

THREAD SAVER FOR SEWING MACHINES

Application filed April 2, 1932. Serial No. 602,796.

This invention relates to devices for preventing thread used in a sewing machine from being lost or wasted when the thread breaks. At the present time, thread coming 5 from a spool or bobbin on a thread supporting stand in certain classes of sewing machines passes through the openings of several guides. In certain classes of machines, one of these guides is located at the top while the 10 other is attached to the bottom of what is known as the bobbin winder of a hosiery knitting machine. There may be several of these guides situated along the path of the thread, all for the purpose of guiding the 15 thread to the proper place of entrance in the bobbin winder.

In the process of sewing, this thread may break and in power driven sewing machines, particularly where a belt is used, the force 20 of the movable parts is such that it causes convection currents of air sufficiently strong to draw the thread into these parts before there is time to shut off the power. Such movement causes the thread to become entangled in the machine, causes considerable 25 loss of thread and a considerable loss of time in cleaning out the jam caused by the thread.

The object of this invention is to provide 30 a thread guide which may be located anywhere along the path that the thread takes in passing down to the undermost bobbin winder which is so constructed that the thread will easily pass through it but which is so formed that if the thread be broken and the 35 free end of the thread should swing off toward a movable part of the machine such as the belt and be pulled thereby, the thread will be cut or else will break so that only a very small amount of the thread will wind 40 around the movable parts so that the waste is negligible and easily cleared away.

A further object is to provide a device of 45 this character which in different forms may be readily applied to any stand or bobbin winder used for sewing or easily built as part of the stand or bobbin winder and which may be applied at a plurality of different places along the course of the thread.

Other objects will appear in the course of 50 the following description.

My invention is illustrated in the accompanying drawing, wherein:—

Figure 1 is an elevation of the rear end of a sewing machine with my thread saving attachments in use thereon;

Figure 2 is an elevation of one of the thread saving attachments;

Figure 3 is an elevation of another form of thread saving attachment;

Figure 4 is a section on the line 4—4 of 60 Figure 2.

Referring to the drawing, it will be seen that in Figure 1, I have illustrated a part of a sewing machine designated A and associated with this sewing machine the vertical 65 supporting member B of a thread stand of an ordinary bobbin winder having the spools C and the upper guides c through which the thread passes. From one of these upper guides c, the thread t is shown as passing 70 downward to the bobbin winder D. The thread t is shown as passing through a bobbin guard or guide d. The bobbin winder is driven by a belt E which engages a pulley on the shaft of the sewing machine head. So 75 far, the parts I have described are old and well-known and are merely shown for illustrative purposes and I have illustrated in Figure 1 two of my thread savers, one disposed between the thread stand and the guide 80 d and the other disposed between the bobbin winder D and the guide d. In Figure 2, I illustrate in detail the device which is applied to the shaft B of the thread stand. This comprises a shank 10 of metal such as steel, 85 the rear end of this shank being enlarged to form an elongated eye 11 having a split or opening 12 on one side and being provided with the set screw 13 extending through the end of the eye at right angles to the slit. 90

The shank 10 under ordinary circumstances is approximately five inches long and at one end is curved outward at 14. The stock of the shank is reduced in thickness at this point by the upwardly extending bevels 15 and terminates in an eye 16. This eye as regards its upper portion is circular in form but the inner end of the eye tapers downward to a V-shaped notch 17. Preferably, though not necessarily, there is a slot 18 which extends 100

from the outer face of the eye inward to the inner face thereof, this slot being preferably inclined upward and preferably having its lower wall beveled at the outer end of the slot as at 19. This slot 18 is for the purpose of threading the eye expeditiously and without the necessity of guiding the extremity of the thread through the eye and the bevel 19 is for the purpose of permitting the ready entrance of the thread into the eye.

The material on each side of the V-shaped notch 17 is beveled to provide the cutting edges 20 which define this V-shaped notch. These cutting edges are very sharp and act 15 when the thread has dropped down into this V-shaped notch to jam the thread and to cut the thread or cause it to break at this point. These cutting edges 20 are razor edges.

It will be seen that I have provided a thread 20 guide, as it may be called, which is so constructed that the thread may easily pass through it, the eye in the end of the shank being sufficiently large to permit this and that at the notch 17 there is situated these 25 razor blades or cutters so that if the thread be drawn laterally, it will come in contact with one or the other of these razor sharp edges and will be severed but so long as the thread runs smoothly in its proper path, it 30 will not be severed.

This deviation of the thread which will cause the thread to be severed is brought about by the tendency of a broken thread to swing toward the movable parts of the machine, this being caused by air currents. Thus, for instance, in Figure 1, I have shown the broken end of the thread *t* as having been drawn over to the belt *E*. Since the parts are toward the machine and this knife edge 40 is also toward the machine, the thread will come in contact with this knife edge and is cut promptly or becomes jammed and is broken. Inasmuch as the thread is cut or broken only a very small amount, that part 45 actually entangled with the belt or other part of the machine is lost. The waste is, therefore, negligible and it requires but an instant to disentangle this small portion of the thread from the machine whereas if the 50 thread is not cut or broken, the continued movement of the machine would draw off quite a large quantity of thread which would become entangled with the machine, have to be severed, and then disentangled.

55 In Figure 4, I illustrate a modified form of this thread saver which is so designed that it may be applied to the table upon which the sewing machine is mounted. This consists of a shank 21 having a base 22 formed with a 60 slot 23 whereby it may be attached to the table of the sewing machine or to any other suitable support. The shank 21 is bent at right angles to the base and at its end is formed with an eye, the axis of which ex- 65 tends at right angles to the sewing machine,

or, in other words, in a horizontal plane. The eye is constructed in exactly the same manner as the eye previously described and the same reference numerals have been used therefor.

It follows, therefore, that if the thread 70 should break between the guide *d* and the bobbin winder *D*, the end of the thread swinging over toward the belt *E*, as it will do, will cause the thread to be brought into the V-shaped notch 17 and severed by the cutting 75 edges 20. The device shown in Figure 2 can be used on the base of any sewing machine and does the same work in the same manner as the device shown in Figure 2. There may be any number of these thread saving 80 devices, however, placed anywhere along the course of the thread. Increasing the number of these devices decreases the chance of the thread being entangled and wasted. The devices are so constructed that they may be inserted on any stand or bobbin winder used for sewing and though, of course, they may be very readily built on a stand or bobbin winder in the manufacture of the stand.

With a device of this character on a machine, much thread can be saved during the course of a working day in a shop of moderate capacity. The thread will break on an average of five or six times a day. This means 95 about \$1.00 per break for the cost of the thread and the time needed to clean the machinery. My device in actual practice has greatly reduced the amount of thread wasted and the amount of time wasted in disentangling the 100 thread. The device is very easily and cheaply constructed and may be applied to any stand.

I claim:

1. A thread saver of the character described, comprising a shank, the shank being 105 formed with a substantially closed eye through which the thread passes, the eye at one point having a V-shaped notch, the opposite walls of the notch being formed with thread cutting edges, the eye, directly opposite the V-shaped notch being smooth and unbroken.

2. A device of the character described, comprising a shank formed at one end with an eye, the outer end of the eye being circular, the inner end of the eye being V-shaped, the V-shaped portion of the eye being provided on its opposite walls with sharp cutting edges whereby if the thread is carried in this V-shaped portion of the eye, it will be cut or 110 broken.

3. A device of the character described, comprising a shank, the outer end of the shank being curved so that the termination of the shank is approximately at right angles to the body of the shank, the terminal end of the shank being formed with an eye through which thread may pass, the upper end of the eye being semi-circular, the lower end of the eye extending downward to a V-shaped notch,

the opposed walls of the notch having sharp cutting edges, the shank immediately beneath the eye being beveled downward and outward.

4. A device of the character described, comprising a shank having at one end an elongated eye and a set screw clamping the shank upon a support, the opposite end of the shank being turned at right angles and the terminal end of the shank being reduced in thickness and formed with an eye, the outer portion of the eye being semi-circular, the inner portion of the eye being formed to provide a V-shaped notch into which the walls of the eye merge gradually, the opposite walls of the V-shaped notch being formed with sharp cutting edges.

In testimony whereof I hereunto affix my signature.

MICHAEL A. SCIULLO.
